US0D1051018S

(12) **United States Design Patent** (10) Patent No.: **US D1,051,018 S**
(45) Date of Patent: ** Nov. 12, 2024

(54) **BIKE CARRIER**

(71) Applicant: **NINGBO CHENFAN AUTO ACCESSORIES CO., LTD**, Zhejiang (CN)

(72) Inventor: **Shouguang Huo**, Zhejiang (CN)

(73) Assignee: **NINGBO CHENFAN AUTO ACCESSORIES CO., LTD**, Zhejiang (CN)

(**) Term: **15 Years**

(21) Appl. No.: **29/862,738**

(22) Filed: **Dec. 12, 2022**

(30) **Foreign Application Priority Data**

Jun. 29, 2022 (CN) 202230404352.9

(51) **LOC (14) Cl.** **12-16**

(52) **U.S. Cl.**

USPC **D12/406**

(58) **Field of Classification Search**

USPC D12/115, 169, 223, 402, 406-408, 412, D12/414-416, 420; D6/552

CPC B60D 1/06; B60D 1/52; E02F 3/7622; B60R 9/06; B60R 9/08; B60R 9/10
